UNITED STATES PATENT OFFICE.

THOMAS GORDON, OF PHILADELPHIA, PENNSYLVANIA, ASSIGNOR TO THE
SIEMENS LUNGREN COMPANY, OF PENNSYLVANIA.

LAMP.

SPECIFICATION forming part of Letters Patent No. 429,441, dated June 3, 1890.

Application filed February 1, 1888. Serial No. 262,681. (No model.)

To all whom it may concern:

Be it known that I, THOMAS GORDON, a citizen of the United States, residing at Philadelphia, in the county of Philadelphia and State of Pennsylvania, have invented certain new and useful Improvements in Regenerative Gas-Lamps; and I do hereby declare that the following is a full, clear, and exact description of the invention, which will enable others skilled in the art to which it appertains to make and use the same.

My invention relates to that class of lamps known as "inverted regenerative lamps," for certain forms of which Letters Patent of the United States were granted to me July 13, 1886, and November 29, 1887, and for which I have filed other applications for Letters Patent, serially numbered, respectively, 217,717, 249,511, and 261,912; and the nature of the present improvement consists in certain modifications in the construction of lamps of this class, hereinafter described and claimed, whereby the gas chamber and burner and other parts of the lamp are so constructed and arranged that they may be readily separated and the parts thereof removed for cleaning and repairs, the central regenerative chamber accurately secured in position, and the parts of the lamp which support the central regenerative chamber and also the outer air-deflector be free to expand or contract.

In the accompanying drawings, Figure 1 represents a vertical section of a lamp on line C D of Fig. 2. Fig. 2 is a horizontal section through line A⁹ B⁹ of Fig. 1. Fig. 3 is a vertical elevation and section on line E F of Fig. 2, showing the means adopted for securing the several parts in place. Fig. 4 is a top view on the right of the center line, showing the arrangement of the gas-inlets, and a bottom view to the left of said line, showing the arrangement of screws for securing the outer air-deflector. Fig. 5 represents a detail view of the center flue. Fig. 6 represents a section and plan of the spider for supporting the center flue and chimney of the lamp, showing in detail the centering-lugs above and below the points of support. Fig. 7 represents a detail view of the outer air-deflector in plan and section.

Referring to the drawings, the gas-burner A is cast of one piece of metal, having rim projections B above and C below the center line of the ribs E. These ribs E are drilled through longitudinally, forming passages for 55 the gas. The spaces F between the tubes thus formed admit of the passage of air downward to the outer surface of the flame.

The gas-chamber G is formed in two sections H and I, having lugs J cast on their peripheries. (See Fig. 3.) These parts being fitted to each other and to the burner to form gas-tight joints, one or more gas-inlet ports K are provided, and the gas-pipes may be connected thereto in such manner as to form supports in suspending the lamp. To the lower surface of section I of the gas-chamber is fitted the globe-holder L, which is secured thereto by a hinge and latch to provide facilities for cleaning or replacing the globe and lighting the lamp. Section I of the gas-chamber has also cast upon its lower inner circumference and projecting downward therefrom a rim M, to which is secured a deflector-plate N. This deflector-plate is provided with lugs O, projecting upward, having smooth holes drilled horizontally through them. The screws P, which serve to support the deflector N, are secured in the rim M, and the ends of the screws are turned to fit smoothly in the holes 80 in lugs O. The deflector N is of somewhat smaller diameter than the inner circumference of the rim M, thus leaving an annular space, through which air may pass to the inner surface of the globe to prevent overheating, &c. Any difference in expansion which may exist between the deflector N and other parts is thus provided for, and the life of these parts is thereby lengthened.

Section H of the gas-chamber is provided 90 with lugs Q at its upper surface projecting inward, the object of which is to form a support for the spider D. Said spider is constructed with ledges R R upon its inner circumference. Projecting downward from said 95 ledges are fingers S, which also project inward and touch the center flue some distance below its point of support. Above the ledges R R, and upon the inner circumference of the collar D² of the spider D, are projections T, 100

which extend inward far enough to touch the outer circumference of the center flue at some distance above the point of support, the object of this arrangement being to maintain 5 the center flue in a plumb and concentric position. An annular rim U is also provided, projecting downward, the object of which is to secure the perforated cylinder V in place. The perforated cylinders V between the 10 downwardly-projecting annular flange U of the spider and the upper surface of the burner surrounding the central escape-flue, and the perforated cylinder W, depending from the lower surface of the burner and surrounding 15 the lower end thereof, serve the purpose of filtering the air-supply and causing it to be delivered to the flame evenly and in smooth currents, preventing flickering and unsteadiness in the light. They also serve to more 20 thoroughly heat the air. The arms D' of the spider D are fitted to the lugs Q of the gas-chamber, section H, in such a manner as to maintain the spider in a position concentric with the other parts of the lamp, (see Figs. 1 25 and 2,) while it is also free to expand and contract without injury to any part of the apparatus. A collar D² is cast upon the spider D, to which is attached the chimney X.

I prefer to construct the center flue R' of 30 one piece of refractory material having lugs R². These lugs are made of such size as to pass readily up through the openings x' of the spider D. The projections T are so placed as to act as stops to prevent the center flue 35 being passed too far up, and the pins or projections T' are provided to prevent accidental displacement of the center flue. With this arrangement it will be impossible to remove the center flue without first having raised it 40 far enough for lugs R² to pass over pins or projections T'.

Having described my invention, what I claim as new, and desire to secure by Letters Patent, is—

45 1. In a regenerative lamp, the combination of a burner, a gas-chamber surrounding the burner, the lower part of which has a cylindrical projection on its bottom to support a deflector, a deflector-plate somewhat smaller 50 in circumference than is the inner circumference of the said rim to allow an annular passage for the air between the deflector and the rim, as and for the purpose described.

2. In a regenerative gas-lamp, the combination of a burner, a gas-chamber formed in 55 two sections surrounding the burner, to the upper section of which is secured a spider supporting the central regenerative chamber, having arms fitted upon said upper section, and a central regenerative chamber depending from said spider and removable therefrom, as and for the purposes described.

3. In a regenerative gas-lamp, the combination of a burner, a gas-chamber formed in 60 two sections surrounding the burner, to the upper section of which is secured a spider supporting the central regenerative chamber,

having arms fitted upon said upper section, and a perforated cylinder depending from the spider, as and for the purposes described.

4. In a regenerative gas-lamp, the combination of a burner, a gas-chamber formed in two sections surrounding the burner, to the upper section of which is secured a spider supporting the central regenerative chamber, 75 having arms fitted upon said upper section, a central regenerative chamber depending from said spider and removable therefrom, and a perforated cylinder depending from the spider, as and for the purposes described. 80

5. In regenerative lamps, the combination of a burner, a gas-chamber provided with lugs Q to form a support for a spider, and a spider supporting the central regenerative chamber, having slotted arms D, which fit 85 upon the lugs Q and travel thereon when the parts are expanded or contracted, as and for the purposes described.

6. A spider constructed with ledges R R upon its inner circumference, fingers S, which 90 project inward and downward and touch the center flue some distance below its point of support, and projections T, extending inward to the center flue, in combination with a center flue having lugs R², as and for the purposes described.

7. The combination of a spider constructed with ledges R R upon its inner circumference, fingers S, which project inward and downward and touch the center flue some 100 distance below its point of support, and projections T, extending inward to the center flue, a center flue having lugs R², and a perforated cylinder V, as and for the purposes described. 105

8. In a regenerative gas-lamp, the combination of a gas-burner cast of a single piece of metal, having ribs drilled through longitudinally, spaces between the tubes thus formed, a spider located above the burner, supporting 110 the central regenerative chamber, and having an annular rim U projecting downward to secure the perforated cylinder V in place, and the perforated cylinder V, as and for the purposes described.

9. In a regenerative lamp, the combination of a burner cast of a single piece of metal, having ribs drilled through longitudinally and spaces between the ribs thus formed, a spider located above the burner, supporting 120 the central regenerative chamber, and having an annular rim U projecting downward to secure the perforated cylinder V in place, the perforated cylinder V, and a perforated cylinder W, as and for the purposes described. 125

10. In combination with a regenerative lamp having a rim M projecting downward therefrom, provided with screws P to support a deflector-plate, a deflector-plate N, having lugs O, provided with holes for the reception of 130 the smooth or cylindrical end of the screws P, as and for the purposes described.

11. In regenerative gas-lamps, the combination of a burner, a gas-chamber supporting a

spider, provided with projections T' upon its inner circumference, a center flue having lugs R² engaging with said projections, as and for the purposes described.

5 12. In a regenerative gas-lamp, the combination of a burner, a gas-chamber, and spider D, secured to said chamber, having ledges R upon its inner circumference, a central

flue depending from said spider, having lugs R² resting upon said ledges, as and for the purposes described.
